APPARATUS FOR CLEANING TANKS AND
THE LIKEClare Richard, Los Angeles, Calif., assignor to
The Pyrate Corporation of Nevada, a corpora-
tion of NevadaApplication July 13, 1934, Serial No. 734,937
Renewed August 10, 1935

23 Claims. (Cl. 299—68)

This invention has to do in a general way with devices for cleaning tanks and the like. It is more particularly related to improvements in devices of the type disclosed in application Serial No. 637,028, filed jointly by myself and Harold M. Ruth on October 10, 1932, and application Serial No. 672,927 filed by Harold M. Ruth on May 26, 1933, both applications being assigned to the assignee in the present case.

10 The device contemplated by this invention like the devices disclosed in the two applications referred to above is especially adapted for use in washing the tanks on tank cars and in oil tankers of their remaining contents subsequent to 15 draining. The general construction of these devices embodies a so-called vertical feed pipe which is suspended through the dome of the tank by suitable means positioned over the dome opening. This main feed pipe carries on its lower end a rotatable secondary feed pipe or housing adapted to rotate about a vertical axis, such 20 secondary feed pipe carrying a nozzle member which is mounted for rotation about its substantially horizontal axis. Means are provided for 25 rotating the nozzle member about its horizontal axis during the passage of a washing fluid therethrough and additional means are provided for effecting a segmental or step by step rotation of the housing which carries the nozzle member 30 about its vertical axis during the rotation of the nozzle member.

It is an important feature of the device contemplated by this invention, like those of the other applications referred to above, that the 35 housing or secondary feed pipe is held stationary during a sufficient period in the rotation of the nozzle member to effect a complete cleaning action on a peripheral circle in the tank's surface.

It is a primary object of the present invention 40 to produce a device of the class described in which the number of the operating parts and the consequent loss in power due to friction in the bearing surfaces is greatly reduced. In line with this object, my invention contemplates an 45 improved mechanism for rotating the housing which carries the nozzle member, such mechanism being constructed so that each step of rotation in the housing is received from the liquid jets projected from the nozzle member as it traverses a certain point in its course. In this 50 manner each step of rotation is imparted to the housing after the complete surface has been covered, regardless of the number of nozzles on the nozzle member. In this connection, it is a further 55 object of my invention to provide, in the

mechanism which rotates the housing, means for regulating or governing the increment of rotation of the housing about its vertical axis.

A preferred form of my invention provides 5 means for automatically varying the increment of rotation from time to time during a single complete rotative movement of the housing about its axis. This provision is made for the purpose of reducing the arc over which the housing rotates and consequently reducing the distance on 10 the surface traversed by the jets between each successive period over which the housing is held stationary during such time as the nozzle members are directed towards the ends of a long 15 tank car.

In another form of my invention I provide adjustable means for varying this increment of rotation. This latter type of construction would probably be more adapted to use in the cleaning 20 of ship tanks and the like where the surfaces are spaced substantially equi-distant from the nozzle member at all points and has the advantage of being adjustable to different sizes of tanks.

The cleaner contemplated by this invention further provides for an improved type of nozzle 25 unit which is constructed so as to facilitate its assembly and further reduce leakage into the nozzle bearings and consequent corrosion and wear therein. This nozzle unit further contemplates means for rotating the nozzle in one direction independently of the nozzle driving means. 30 Such means permits the placement of the nozzle at any desired position to facilitate its installation and removal from a tank.

In the device contemplated by this invention 35 I provide a turbine member for effecting the rotation of the nozzle member about its horizontal axis. This turbine member is mounted directly upon the housing or secondary feed pipe which carries the nozzle member. My invention further 40 contemplates improvement in the turbine means whereby the speed of the nozzle operation can be easily and quickly regulated. My invention further contemplates an improved means for effecting the lubrication of the turbine shaft, such 45 means being provided with an automatic cut-off which shuts off the supply of lubricant as soon as the pressure liquid or washing fluid is shut off.

Another object of this invention is to provide, 50 in a device of the class described, an improved dome spray which does not embody any moving parts but which is so constructed as to reach all parts of a tank dome.

A still further object of my invention is to 55 provide a device of the class described with an

improved type of indicator whereby the operator can immediately determine when the tank has been completely cleaned and can further determine at any time to what extent the cleaning 5 has been made.

The details in the construction of a preferred form of my invention together with other objects attending its production will be best understood from the following description of the accompanying drawings which are chosen for illustrative purposes only, and in which

Fig. 1 is an elevational view with parts in section showing a preferred form of my invention suspended through the dome of a tank.

Fig. 2 is a fragmentary side view of the device shown in Fig. 1 and is taken in the general direction of the arrow 2 in that figure.

Fig. 3 is a sectional view taken in the plane represented by the line 3—3 of Fig. 2.

Fig. 4 is a fragmentary section taken in a plane represented by the line 4—4 of Fig. 3.

Fig. 5 is an enlarged sectional view taken in a plane represented by the line 5—5 in Fig. 1 and illustrating further details in the preferred form 25 of lubricating control means.

Fig. 6 is an enlarged view showing a fragment of the nozzle member illustrated in Fig. 3.

Fig. 7 is an enlarged fragmentary view taken in the general direction of the arrow 1 of Fig. 1.

Fig. 8 is an end elevation taken in the general direction of the arrow 8 on Fig. 3 and is partly broken away to show further details in the construction of the reservoir which delivers the pressure liquid to the turbine nozzle.

Fig. 9 is a sectional elevation taken in a plane represented by the line 9—9 in Fig. 8.

Fig. 10 is an enlarged fragmentary view showing further details in the construction of the mechanism which is employed for effecting the 40 step by step rotation of the housing.

Fig. 11 is an end view with parts broken away which may be considered as having been taken in the direction of the arrow 11 on Fig. 10.

Fig. 12 is a fragmentary view more or less diagrammatic in character and illustrating the mechanism whereby I obtain varying increments of movement of the housing for each complete rotation thereof; and

Fig. 13 is an elevational view illustrating a 50 modified form of mechanism for regulating the throw of the ratchet member or the means for rotating the housing about its vertical axis.

More particularly describing the invention as herein illustrated, reference numeral 11 indicates 55 the top of a tank or the dome of a tank car which is provided with an opening 12 having a downwardly projecting flange 13. The device contemplated by this invention is generally indicated by reference numeral 14 and consists in a general 60 way of a cover plate or supporting member 15 which carries a vertical main feed pipe 16, the lower end of which supports a rotatable secondary feed pipe or housing 17 which, in turn, is provided with a nozzle assembly 18 supported so as 65 to rotate about its substantially horizontal axis.

The plate or cover member 15 is locked in place over the opening in the tank or dome by means of a lock-screw 19 which has a wedge member 20 on its lower end adapted to fit under 70 flanges of various widths in openings of various diameters. The plate member 15 is provided with a central opening 21 into which a plurality of webs 22 extend to provide a support for a sleeve member 23. The upper end of the sleeve member 23 is provided with a collar 24 which carries 75

an internally threaded nut member 25 provided with a hand wheel 26. The nut member 25 engages threads 27 formed on the outer surface of the main feed pipe 16 and these two elements co-operate to effect vertical adjustment of the 5 main feed pipe and its associated parts relative to the top of the tank.

The top of the main feed pipe is provided with a T-fitting 28 to which a conduit 29 is connected for delivering washing fluid under pressure into the main feed pipe. A baffle plate 30 is provided at the lower edge of the web member to prevent the splashing of the washing liquid through the central opening in the main plate and the bottom of the sleeve member 22 is connected to a nipple 31 which, in turn, receives a T-fitting 32, such T-fitting being connected at its lower end to a second sleeve member 33 which extends a substantial distance down into the tank. The inlet to the T-fitting 32 is shown as being 20 connected through a bushing 34 with a steam-inlet pipe 35 and the lower end of the sleeve 33 is provided with openings 36 for admitting steam to the tank when desired. Handles 37 and 37' are also shown as being provided on the lower end of 25 the sleeve member 33 to facilitate handling the unit.

As has been previously pointed out, the device contemplated by this invention embodies a nozzle member adapted to continuously rotate about a 30 substantially horizontal axis, such nozzle member being rotatably mounted upon a secondary feed pipe or housing which, in turn, receives step by step or intermittent rotation about a substantially vertical axis.

It is an important feature of the present invention that the nozzle member is positively driven by a turbine which, in turn, is operated by the pressure fluid delivered into the system, and the housing or secondary feed pipe is intermittently rotated about its axis through a mechanism which is operated by the jets of power liquid projected from the nozzle member.

The details in the construction of the nozzle unit, the housing and the mechanism for effecting the rotation of these parts will be best understood by reference to Figs. 2 to 13, inclusive. In this form of my invention, the housing 17 is shown as comprising a casting 40 which has a vertical conduit section 41 which, in turn, receives the extreme lower end of the main feed pipe 16.

The lower end of the conduit section 41 is provided with an inwardly projecting annular shoulder 43. Reference numeral 43' indicates packing material which is interposed between the 55 shoulder 43 and the bottom of the main feed pipe. The top of the section 41 is provided with an enlargement 44 which receives an annular flange 45, such flange supporting roller bearings 46 which, in turn, are engaged by a ring nut 47 mounted 60 in threaded engagement with the enlargement 44. The bearing just described constitutes a rotatable support for the housing on the main feed pipe 16. The bottom of the conduit section 41 is provided with a transverse passage 41T, one 65 side of which is threaded to receive a nozzle feed pipe or hollow axle 48. The axle 48 is threaded at its outer end to receive a bearing nut 50 which acts to hold a nozzle hub member 51 on the hollow axle. The interior of the nozzle hub member 51 is provided with flanges 52 and roller bearings 53 are interposed between such flanges and the co-operating bearing surfaces on the hollow axle. Reference numeral 55 indicates a nozzle member shown as being provided with two dia- 75

metrically opposed nozzles 56 and 56'. This nozzle member is secured to the nozzle hub member through the medium of flanges 57 and 57' and screws 58 extending into the nozzle member. The 5 nozzle member has a central passage 60 situated in alignment with the hollow passage through the hollow axle or nozzle feed pipe 48, and has a bearing face surrounding such passage which bears against the end face on the hollow axle.

10 For the purpose of reducing leakage into the hub member to a minimum I provide the nozzle member in this form of my invention with an annular groove 61 surrounding the passage 60, such groove containing a ring 62 which is adapted 15 to be forced into pressure engagement with the bearing face on the end of the hollow axle by means of pressure fluid entering the groove 61 through ports 63.

10 The nozzle member and its associated parts 20 constituting the nozzle assembly 18 are adapted to be driven through the medium of a gear 65 which, in order to permit the manual rotation of the nozzle member, is loosely mounted upon the hub and imparts its rotation thereto through the 25 medium of pawls 67 pressed inwardly by springs 66 which are mounted within chambers 68 formed in an annular flange 69 on the gear 65. These pawls engage ratchet notches 67' formed in the nozzle hub 51. The gear and its associated parts 30 are shown as being protected by a gear protecting housing 70 formed integrally with the housing 17.

35 The gear which in this instance is in the nature of a worm wheel is adapted to be driven by a worm wheel 71 mounted upon a worm shaft 72 which extends through a suitable bearing 73 in the protecting housing 70 and is provided on its other end with a worm wheel 74. The worm wheel 74 is engaged by a worm 75 mounted on the end of a turbine shaft 76 which extends through a 40 boss 77 formed on the housing 17. This turbine shaft is mounted in roller bearings generally indicated by reference numeral 78 and carries on its opposite end a turbine wheel indicated by reference numeral 79. The turbine wheel 79 is protected by a turbine housing 80 and is adapted to be 45 driven by jets of power liquid projected from nozzle members indicated at 82 and 83. The nozzle members 82 and 83 are mounted for vertical and longitudinal adjustment in nozzle housings 50 which are also shown as being cast integrally with the main housing 17.

55 The details in the mounting of the turbine nozzles 82 and 83 are best illustrated in Fig. 9 where the nozzle members are shown as having an undercut portion 84 situated opposite a set-screw 85 extending through the wall of the turbine nozzle housing. By constructing the turbine nozzles in this manner I am enabled to effect both lateral and longitudinal adjustments, thereby 60 obtaining an accurate control over the speed of the unit.

65 The power liquid for operating the turbine is delivered to the turbine nozzle through conduits 86 and 87 which lead to what I may term a turbine nozzle supply reservoir 89 which is formed on the end of the transverse passage 41T opposite the nozzle assembly, and is provided with a closure plug 90. In order to prevent the admission of sediment etc. into turbine nozzle passages 70 I provide a screen 91 which fits against shoulder 92 formed in the outer end of the transverse passage 41T, such screen being held against the shoulder 92 by means of a projecting flange 93 on the closure plug 90. This construction provides 75 an annular chamber 95 surrounding the

reservoir between the screen 91 and the plug 90. Liquid is delivered into the annular chamber 95 through ports 96 in the flange 93, and the conduits 86 and 87 are mounted in the wall of the annular chamber as is clearly illustrated by the 5 broken away section of Fig. 8.

It will be seen from the construction so far described that when a pressure liquid is delivered into the main feed conduit, such liquid passes downwardly into the housing and through the 10 nozzle member. A portion of such liquid is carried by the conduits 86 and 87 to the turbine nozzles where it is impinged upon the vanes of the turbine wheel, thereby effecting its rotation and consequently rotating the nozzle member 15 through the associated shafts, worms and the nozzle tube.

It was previously pointed out as one object of this invention to provide means for insuring lubrication of the turbine shaft, such means being associated with an automatic valve cut-off whereby the supply of lubricant is stopped when the device is not in operation. In this form of my invention the lubricating system comprises a visible reservoir 100 which is situated outside of 20 the main feed shaft and at a point where it can always be inspected by the operator. The lubricant reservoir is mounted on the top of a lubricant feed pipe 101 which extends downwardly through a packing gland in the top of the T-fitting 25 28 to a point at the bottom of the housing 17 where it is received in a threaded opening 102, such opening extending clear through the bottom of the housing and receiving a second conduit 103 in its lower end. The pipe or conduit 30 103 extends upwardly to a bushing 104 which is received in an enlarged opening 105 formed in a cap member 106 which is secured to a boss 107 formed on the face of the main housing 17 through the medium of screws 108. The inner 35 end of the chamber 105 is provided with a valve seat 110 against which a ball valve 111 is pressed by means of a compression spring 112. The ball valve 111, when in its normal position, is effective to close a passage 113 which extends through the 40 shaft and communicates with a groove 117 extending upwardly through a transverse passage 118 leading to the turbine shaft. The passage 113 is provided with a grooved or flat-sided pin 120, the inner of which bears against a diaphragm 121 interposed between the cap 106 and the boss 107. The diaphragm is held in spaced 45 relation with the boss and the cap by means of washers 123 which have openings therein forming part of the passage 118. Pressure liquid from the 50 washing system is delivered against the diaphragm through a conduit 124 formed in the turbine housing 82', a second conduit 125 formed in the casting and leading upwardly therefrom and a third conduit 126 communicating directly 55 with the face of the boss.

It will be seen from this construction that as soon as pressure liquid enters the system some of such liquid will pass through the conduits just recited applying pressure to the diaphragm, 65 thereby forcing the pin 113 to the left, pushing the valve off its seat and admitting the passage of lubricant along the flat face or the groove in the pin into the ducts communicating with the turbine shaft.

70 As has been previously pointed out the segmental or step by step rotation of the housing about its vertical axis in this form of my invention is effected through the medium of the jets of pressure liquid projected from the nozzle. This 75

operation is obtained through the medium of what I may term a vane member 130 which is loosely mounted upon a ratchet and worm shaft 131 which, in turn, is carried by bearings 132 in a standard 134 mounted upon the main housing 17, the vane member being positioned so that it extends substantially across the plane of rotation of the nozzle member 18. As is clearly illustrated in Fig. 11, the vane member 130 is of relatively narrow construction and is shown as being wedge shaped on its lower surface. The ratchet and worm shaft 131 carries a ratchet wheel 136 which is situated adjacent to the vane member 130. Such ratchet wheel is engaged by a pawl member 137 pivotally mounted upon the side of the vane member and pressed downwardly toward the ratchet wheel by means of a spring 138. A lock or retaining pawl 139 is shown as being mounted upon a pin 140 which is screwed into the face of the standard 134. The outer end of the worm and ratchet shaft 131 is provided with a worm 142, such worm engaging a worm wheel 143 which is rigidly mounted upon the main feed pipe above the bearing for the rotatable housing or secondary feed pipe. The mechanism just described is provided with a protecting sheath mounted upon the top of the housing 17.

It will be seen that, during the operation of the unit, as each nozzle traverses a point beneath the vane 130, the jet projected from that nozzle will react upon the vane, pushing the same upward, thereby throwing the ratchet wheel, rotating the worm and effecting a segment of rotation of the entire housing and its associated parts about the worm wheel 143, the extent of such rotation being dependent upon the throw of the ratchet wheel. It was previously pointed out as one object of this invention to provide, in a mechanism of the class just described, means for varying the segment of rotation from time to time during a complete rotation of the housing about its axis. In the form of my invention shown in Figs. 1 to 12, inclusive, I accomplish this last objective by providing on the lower forward end of the vane member a shoulder boss 150. Immediately below the forward end of this shoulder boss 150 I provide a vertically reciprocating stop pin 151, which is slidably mounted in a projection 152 and is pivotally attached at its lower end to a lever member 153, such member being pivoted to the housing through the medium of a screw 154. The other end of the lever member is pivotally attached to the lower end of what I may term a cam operated plunger 155, the upper end of which is provided with a roller or follower 156 which is pressed upwardly against a face cam 157, formed integrally with the main feed pipe below the worm wheel 143, by a compression spring 156'.

In the form shown, the face cam 157 has two levels L1 and L2 and it will be seen that when the follower is bearing upon the level L2 the stop is lifted a substantial distance beyond what it was when the follower was bearing upon the level L1. Thus it will be seen that the throw of the ratchet and the consequent segment of rotation in the housing will be reduced during such time as the follower engages the lever L2. In mounting a device of this character in a tank car it will be customary to so position the cam so that the throw is reduced when the nozzles are directed towards the end portions of the car, thereby reducing the arc traversed by the stream 75 and compensating for the greater distance over

which the stream must travel before it reaches the surface to be washed.

It will be observed as a distinct advantage of this device that the housing is given a segment of rotation each time the periphery of the tank 5 has been traversed by the washing stream regardless of the number of nozzles on the nozzle member.

In order to effect a complete and thorough cleaning of the dome during the operation of a 10 device of this character in a tank car, I provide upon the sleeve 33, directly above the nozzle assembly, a cone or deflecting member 160 which is upwardly divergent so that a portion of the nozzle stream as it traverses its upward course 15 is directed into the roof of the dome. In addition to this cone or deflecting member I provide, for the purpose of washing the walls of the dome, a plurality of dome washing nozzles 161 which are shown as being mounted in an annular wall 20 section 162 which in turn is secured by welding or in any other suitable manner to the sleeve 133 so as to form a closed chamber about such sleeve. Washing liquid is delivered into this enclosed chamber, indicated by reference numeral 163, through an auxiliary conduit 164 which, in turn, is connected through a suitable conduit 165 with the T-fitting 28 on the top of the main feed conduit.

It was also pointed out as one object of this 30 invention to provide an improved indicator whereby the operator could determine to just what extent the washing operation has been carried and could also determine when the tank had been completely cleansed. In this form of my 35 invention, the indicator is shown as comprising a short shaft 170, slidably and rotatably mounted in a suitable bracket 171 which is secured to the top of the main feed conduit. The outer end of this short shaft is provided with a needle 172 40 which rotates against a disk 173 and is provided with a knurled knob 174 to facilitate its being set. The inner end of the short shaft 170 is provided with a pinion 174 which engages another pinion 175, preferably of the same size as the 45 first, the latter pinion being rigidly secured to the oil feed conduit 106. It will be understood, from the manner of mounting the oil feed conduit, that such conduit rotates directly with the housing and as it rotates it will obviously rotate 50 the needle 172, the gears being in the same ratio, one complete rotation of the needle indicating that the housing has turned through 360° thereby completely cleansing the interior of the tank. The pinion 174 is held in mesh with the pinion 55 175 by means of a compression spring 176 and it will be seen that this construction permits withdrawing the gears from mesh and setting the needle at a predetermined point.

For the purpose of handling the unit and to 60 protect the oil reservoir and associated parts, I provide the top of the main feed conduit with an upwardly extending stirrup 177. Reference numeral 178 indicates a downwardly projecting pin or leg which is used to support the unit when it is 65 not in use.

In Fig. 13 I show a modified form of control means whereby the segmental rotation in the housing can be adjusted at will for any pre-determined arc. In this figure all of the elements 70 similar to those shown in Fig. 10 are indicated by the same reference numerals distinguished by the letter "a". The main distinction between this form of my invention and that shown in Fig. 10 resides in the stop member 151a which is 75

adapted to be engaged by the stop shoulder 150a on the vane member for limiting the throw of the ratchet. In this latter form of my invention, the stop 151a is formed on the upper end of a screw 180, such screw being provided with a lock nut 181 to hold it in the desired position of adjustment.

It will be apparent from the foregoing description that my invention contemplates a construction which permits the mounting of all rotating parts on roller bearings, reduces the number of moving parts below that in either of the applications referred to in the first part of this specification and thereby greatly increases the ease with which the device may be operated and controlled. It is to be understood that, while I have herein illustrated one preferred form of my invention, the invention is not limited to the precise construction disclosed herein but includes within its scope whatever changes fairly come within the spirit of the appended claims.

I claim as my invention:

1. A tank cleaning device of the class described embodying: a main feed pipe; means for vertically supporting said main feed pipe; a secondary feed conduit rotatably mounted on the lower end of said main feed pipe; a nozzle feed pipe mounted on said secondary feed conduit at an angle thereto; a nozzle member rotatably mounted on said nozzle feed pipe; a liquid motor supported by said secondary feed conduit and rotatable therewith; means for delivering power liquid to the motor from said secondary feed conduit; means operated by said liquid motor for rotating said nozzle member on said nozzle feed pipe; and means intermittently operated by a liquid jet projected from said nozzle member for effecting step by step rotation of said secondary feed conduit on said main feed pipe.

2. A tank cleaning device of the class described embodying: a main feed pipe; means for vertically supporting said main feed pipe; a secondary feed conduit rotatably mounted on the lower end of said main feed pipe; a nozzle feed pipe mounted on said secondary feed conduit at an angle thereto; a nozzle member rotatably mounted on said nozzle feed pipe; a liquid motor supported by said secondary feed conduit and rotatable therewith; means for delivering power liquid to the motor from said secondary feed conduit; means operated by said liquid motor for rotating said nozzle member on said nozzle feed pipe; and ratchet means intermittently operated by a liquid jet projected from said nozzle member for effecting step by step rotation of said secondary feed conduit on said main feed pipe.

3. A tank cleaning device of the class described embodying: a main feed pipe; means for vertically supporting said main feed pipe; a secondary feed conduit rotatably mounted on the lower end of said main feed pipe; a nozzle feed pipe mounted on said secondary feed conduit at an angle thereto; a nozzle member rotatably mounted on said nozzle feed pipe; a liquid motor supported by said secondary feed conduit and rotatable therewith; means for delivering power liquid to the motor from said secondary feed conduit; means operated by said liquid motor for rotating said nozzle member on said nozzle feed pipe; means intermittently operated by a liquid jet projected from said nozzle member for effecting step by step rotation of said secondary feed conduit on said main feed pipe; said last mentioned means including a vane pivotally mounted on said secondary feed conduit and extending across

the plane of rotation of said nozzle member, ratchet means operably associated with said vane; and means operated by said ratchet means for imparting segmental rotation to said secondary feed conduit.

4. A tank cleaning device of the class described embodying: a main feed pipe; means for vertically supporting said main feed pipe; a secondary feed conduit rotatably mounted on the lower end of said main feed pipe; a nozzle feed pipe mounted on said secondary feed conduit at an angle thereto; a nozzle member rotatably mounted on said nozzle feed pipe; a liquid motor supported by said secondary feed conduit and rotatable therewith; means for delivering power liquid to the motor from said secondary feed conduit; means operated by said liquid motor for rotating said nozzle member on said nozzle feed pipe; means intermittently operated by a liquid jet projected from said nozzle member for effecting step by step rotation of said secondary feed conduit on said main feed pipe; said last mentioned means including a vane pivotally mounted on said secondary feed conduit and extending across the plane of rotation of said nozzle member; a pawl member mounted on said vane, a ratchet wheel rotatably supported by said secondary feed conduit and engaged by said pawl, and means actuated by said ratchet wheel for imparting segmental rotation to said secondary feed conduit.

5. A tank cleaning device of the class described embodying: a main feed pipe; means for vertically supporting said main feed pipe; a secondary feed conduit rotatably mounted on the lower end of said main feed pipe; a nozzle feed pipe mounted on said secondary feed conduit at an angle thereto; a nozzle member rotatably mounted on said nozzle feed pipe; a liquid motor supported by said secondary feed conduit and rotatable therewith; means for delivering power liquid to the motor from said secondary feed conduit; means operated by said liquid motor for rotating said nozzle member on said nozzle feed pipe; means intermittently operated by a liquid jet projected from said nozzle member for effecting step by step rotation of said secondary feed conduit on said main feed pipe; said last mentioned means including a vane pivotally mounted on said secondary feed conduit and extending across the plane of rotation of said nozzle member, a pawl member mounted on said vane, a ratchet wheel engaging said pawl member, a shaft supported by said secondary feed conduit carrying said ratchet wheel, a worm on said shaft, and a worm wheel rigidly mounted on said main feed conduit engaging said worm.

6. A tank cleaning device of the class described embodying: a main feed pipe; means for vertically supporting said main feed pipe; a secondary feed conduit rotatably mounted on the lower end of said main feed pipe; a nozzle feed pipe mounted on said secondary feed conduit at an angle thereto; a nozzle member rotatably mounted on said nozzle feed pipe; means for rotating said nozzle member on said nozzle feed pipe; and means intermittently operated by a liquid jet projected from said nozzle member for effecting step by step rotation of said secondary feed conduit on said main feed pipe.

7. A tank cleaning device of the class described embodying: a nozzle member; housing means rotatably supporting said nozzle member for rotation about a substantially horizontal axis; means rotatably supporting said housing for rotation about a vertical axis; means for rotating

- said nozzle member and means intermittently operated by a liquid jet projected from said nozzle member for effecting step by step rotation of said housing on its supporting means.
- 5 8. A tank cleaning device of the class described embodying: a nozzle member; a housing communicating internally with said nozzle member and supporting same for rotation about a substantially horizontal axis; a main feed conduit 10 communicating internally with said housing and supporting same for rotation about a substantially vertical axis; means for rotating said nozzle member about its axis; and ratchet means intermittently actuated by a liquid jet projected from 15 said nozzle member for effecting step by step rotation of said housing about its axis.
9. A tank cleaning device of the class described embodying: a nozzle member; a housing communicating internally with said nozzle member 20 and supporting same for rotation about a substantially horizontal axis; a main feed conduit communicating internally with said housing and supporting same for rotation about a substantially vertical axis; means for rotating said nozzle member about its axis; and means intermittently actuated by a liquid jet projected from 25 said nozzle member for effecting step by step rotation of said housing about its axis; said last mentioned means including a vane pivoted to said housing 30 and extending across the plane of rotation of said nozzle member, ratchet means operably associated with said vane, and means operated by said ratchet means for imparting segmental rotation to said housing.
- 35 10. A tank cleaning device of the class described embodying: a nozzle member; a housing communicating internally with said nozzle member and supporting same for rotation about a substantially horizontal axis; a main feed conduit 40 communicating internally with said housing and supporting same for rotation about a substantially vertical axis; means for rotating said nozzle member about its axis; and means intermittently actuated by a liquid jet projected from 45 said nozzle member for effecting step by step rotation of said housing about its axis; said last mentioned means including a vane pivoted to said housing and extending across the plane of rotation of said nozzle member, a pawl member mounted on said 50 vane, a ratchet wheel rotatably supported by said housing and engaged by said pawl, and means actuated by said ratchet wheel for imparting segmental rotation to said housing relative to said main feed conduit.
- 55 11. A tank cleaning device of the class described embodying: a nozzle member; a housing communicating internally with said nozzle member and supporting same for rotation about a substantially horizontal axis; a main feed conduit 60 communicating internally with said housing and supporting same for rotation about a substantially vertical axis; means for rotating said nozzle member about its axis; and means intermittently actuated by a liquid jet projected from 65 said nozzle member for effecting step by step rotation of said housing about its axis; said last mentioned means including a vane pivotally mounted on said housing and extending across the plane of rotation of said nozzle member, a pawl member mounted on said vane, a ratchet wheel engaging said pawl, a shaft secured to said ratchet wheel, bearing means on said housing supporting said shaft, a worm on said shaft, and a worm wheel rigidly mounted on said main feed 70 conduit engaging said worm.
- 75 12. A tank cleaning device of the class described embodying: a nozzle member; a housing communicating internally with said nozzle member and supporting same for rotation about a substantially horizontal axis; means for rotating said nozzle member about its axis; a main feed conduit communicating internally with said housing and supporting same for rotation about a substantially vertical axis; ratchet means intermittently actuated by a liquid jet projected from 80 said nozzle member for effecting step by step rotation of said housing about its axis; and means associated with said ratchet means for automatically varying the rotative increments of said housing over predetermined intervals in a single 85 rotation thereof.
13. A tank cleaning device of the class described embodying: a nozzle member; a housing communicating internally with said nozzle member and supporting same for rotation about a substantially horizontal axis; means for rotating said nozzle member; a main feed conduit communicating internally with said housing and supporting same for rotation about a substantially vertical axis; means intermittently actuated by a liquid jet projected from 90 said nozzle member for effecting step by step rotation of said housing about its axis comprising a vane pivoted to said housing and extending across the plane of rotation of said nozzle member, a pawl mounted on said vane, a shaft rotatably mounted on said housing adjacent said pawl, a ratchet wheel on said shaft engaged by said pawl, a worm on said shaft, and a worm wheel rigidly mounted on said main feed conduit engaging said worm; and means 95 for automatically varying the rotative increment of said housing over predetermined intervals in a single rotation thereof comprising a shoulder on said vane member, a stop member slidably mounted in said housing for engaging with said shoulder, a face cam rigidly secured to said main feed pipe, a follower slidably mounted in said housing and engaging said cam, and lever means interconnecting said follower and said stop member.
14. A tank cleaning device of the class described embodying: a nozzle member; a housing communicating internally with said nozzle member and supporting same for rotation about a substantially horizontal axis; means for rotating said nozzle member about its axis; a main feed conduit 40 communicating internally with said housing and supporting same for rotation about a substantially vertical axis; ratchet means intermittently actuated by a liquid jet projected from 45 said nozzle member for effecting step by step rotation of said housing about its axis; and stop means for limiting the throw of said ratchet means, thereby controlling the increment of rotation of said housing.
- 50 15. A tank cleaning device of the class described embodying: a nozzle member; a housing communicating internally with said nozzle member and supporting same for rotation about a substantially horizontal axis; means for rotating said nozzle member about its axis; a main feed conduit 55 communicating internally with said housing and supporting same for rotation about a substantially vertical axis; ratchet means intermittently actuated by a liquid jet projected from said nozzle member for effecting step by step rotation of said housing about its axis; and adjustable stop means for limiting the throw of said ratchet means, thereby controlling the increment of rotation of said housing.
- 60 16. For use in a tank cleaning device of the 75

class described, the combination of: a nozzle member; a housing having a passage therethrough communicating with said nozzle member and supporting same for rotation about a substantially horizontal axis; means for delivering a pressure liquid into said housing; a turbine wheel rotatably mounted on said housing; means operated by said turbine wheel for driving said nozzle member; a turbine nozzle positioned to direct a liquid jet against the vanes in said turbine wheel; and means for delivering pressure liquid from said housing to said turbine nozzle comprising a reservoir communicating internally with the passage through said housing, a strainer mounted in the entrance to said reservoir, and a conduit leading from said reservoir to said turbine nozzle.

17. For use in a tank cleaning device of the class described, the combination of: a nozzle member; a housing having a passage therethrough communicating with said nozzle member and supporting same for rotation about a substantially horizontal axis; means for delivering a pressure liquid into said housing; a turbine wheel rotatably mounted on said housing; means operated by said turbine wheel for driving said nozzle member; a turbine nozzle adjustably mounted on said housing adjacent said turbine wheel for directing a liquid jet against the vanes thereof; and conduit means for delivering pressure liquid from said housing to said turbine nozzle.

18. For use in a tank cleaning device of the class described, the combination of: a nozzle member; a housing communicating internally with said nozzle member and supporting same for rotation about a substantially horizontal axis; means for delivering a pressure liquid into said housing; a turbine shaft; bearing means on said housing supporting said shaft; a turbine wheel on said shaft; means for delivering pressure liquid from said housing to said turbine wheel for driving same; gear means associated with said shaft for driving said nozzle member; and means for delivering oil to said shaft during the operation of said turbine comprising an oil reservoir, a conduit for delivering oil from said reservoir to said shaft, a valve in said conduit, yieldable means for normally holding said valve closed, and means automatically operated by pressure fluid from said housing for opening said valve.

19. For use in a tank cleaning device of the class described, the combination of: a nozzle member; a housing communicating internally with said nozzle member and supporting same for rotation about a substantially horizontal axis; means for delivering a pressure liquid into said housing; a turbine shaft; bearing means on said housing supporting said shaft; a turbine wheel on said shaft; means for delivering pressure liquid from said housing to said turbine wheel for driving same; gear means associated with said shaft for driving said nozzle member; and means for delivering oil to said shaft during the operation of said turbine comprising an oil reservoir, a conduit for delivering oil from said reservoir to said shaft, a valve in said conduit, yield-

able means for normally holding said valve closed, and means comprising a diaphragm actuated by pressure fluid from said housing and a pin interposed between said diaphragm and said valve for automatically opening said valve when pressure fluid is in said housing.

20. For use in a tank cleaning device of the class described, a nozzle unit embodying: a hollow axle; a bearing flange on the inner end of said hollow axle; a hub member on said hollow axle; a bearing nut on the outer end of said hollow axle; anti-friction bearings interposed between said bearing flange, said bearing nut and said hub member; flange means on the outer end of said hub member; and a nozzle member secured to said flange means, said nozzle member having a central opening communicating with the passage through said hollow axle.

21. For use in a tank cleaning device of the class described, a nozzle unit embodying: a hollow axle; a bearing flange on the inner end of said hollow axle; a hub member on said hollow axle; a bearing nut on the outer end of said hollow axle; anti-friction bearings interposed between said bearing flange said bearing nut and said hub member; flange means on the outer end of said hub member; a nozzle member secured to said flange means, said nozzle member having a central opening communicating with the passage through said hollow axle; and a bearing face engaging the end face of said hollow axle.

22. For use in a tank cleaning device of the class described, a nozzle unit embodying: a hollow axle; a bearing flange on the inner end of said hollow axle; a hub member on said hollow axle; a bearing nut on the outer end of said hollow axle; anti-friction bearings interposed between said bearing flange said bearing nut and said hub member; flange means on the outer end of said hub member; a nozzle member secured to said flange means, said nozzle member having a central opening communicating with the passage through said hollow axle and an annular groove in its inner face opposite the outer end face on said hollow axle; a bearing ring in said annular groove; and ports leading from said annular groove to the interior of said nozzle member for applying pressure fluid to said bearing ring.

23. For use in a tank cleaning device of the class described, a nozzle unit embodying: a hollow axle; a bearing flange on the inner end of said hollow axle; a hub member on said hollow axle; a bearing nut on the outer end of said hollow axle; anti-friction bearings interposed between said bearing flange said bearing nut and said hub member; flange means on the outer end of said hub member; a nozzle member secured to said flange means, said nozzle member having a central opening communicating with the passage through said hollow axle; a gear member rotatably mounted on the inner end of said hub; and ratchet means interposed between said gear and said hub and forming a uni-directional lock therebetween.
